UNITED STATES PATENT OFFICE.

JOHN E. STEMPLE, OF BLOOMINGTON, INDIANA.

BASKET-BALL SCORE CARD.

Application filed September 1, 1922. Serial No. 585,580.

To all whom it may concern:

Be it known that JOHN E. STEMPLE, citizen of the United States, residing at Bloomington, in the county of Monroe and State 5 of Indiana, has invented certain new and useful Improvements in Basket-Ball Score Cards, of which the following is a specification, reference being had therein to the accompanying drawings.

10 The invention relates to basket ball score cards, and has for its object to provide a device of this character wherein a complete record of the plays and a summary of the plays of competing teams may be easily 15 and quickly made. Also to form the score card record in a compact form.

A further object is to provide a basket ball score card for competing basket ball teams, the score card being provided for 20 each team with columns indicating the positions of the players, the numbers of the players, the names of the players, the time played for the first and second half, a plurality of numbers for the first half, which 25 may be checked for indicating the number of shots which the player takes at the basket and the number of times a player assists another player in scoring, a column for the points scored on the first half, a column 30 having a plurality of numbers indicating the time of the second half, a column in which the points scored in the second half may be placed and a summary.

A further object is to provide a summary 35 adjacent the bottom of the score card, a space for remarks and for substitutes; also for the name of the umpire, the timers, scorers, place and date of the game, time and the referee.

40 With the above and other objects in view the invention resides in the combination and arrangement of parts as hereinafter set forth, shown in the drawings, described and claimed, it being understood that changes 45 in the precise embodiment of the invention may be made within the scope of what is claimed without departing from the spirit of the invention.

In the drawings:—

50 Figure 1 is a plan view of the left hand side of the score card.

Figure 1^a is a plan view of the right hand side of the score card.

55 Referring to the drawings, the numeral 1 designates vertically disposed columns which indicate the various positions of the players

of the contending teams, and 2 columns in which may be written the numbers of the players of contending teams. Following the columns 2 are columns 3, in which the names 60 of the players may be written. To the right of the columns 3 are columns 4 in which the time played may be indicated and following the time played columns are 65 columns 5, indicating the first half of the 70 contending teams and a plurality of numbers 6, any one of which may be checked for summary purposes, for indicating the number of shots which the player takes at the basket and the number of times a player 75 assists another player in scoring. Disposed to the right of the columns 5 are vertical columns 7, in which columns the points 80 scored on the first and second halves of the contending teams may be written. Following the columns 7, and to the right of the columns 7 are columns 8 similar to the columns 5, but utilized for recording the second half, and to the right thereof columns 9 similar to columns 7 are provided in which 85 the points scored on the second half may be recorded. Following to the right of the columns 9 are summary columns 10, in which 90 columns may be recorded a summary of the plays of the various players. It will be seen that a complete record of the individual players may be maintained for each of the contending teams. Disposed below the score cards of the individual players are horizontally disposed recording spaces in which 95 the score of the individual teams may be recorded, said spaces being designated by the numeral 11 and terminating in final score spaces 12. Disposed beneath the spaces 11 between the lines 13 are horizontally 100 disposed lines and spaces, in which may be written a further record of the teams as a whole, for instance field attempts, goals and the like, and beneath the lower line 13 are disposed horizontally disposed lines 15, on 105 which may be written the names of substitutes, and on lines 16 any remarks may be written. The bottom of the score is provided with a line for the names of the timers, 110 said line being designated by the numeral 17, a line 18 for the names of the scorers, a line 19 for the name of the umpire and a line 20 for the name of the place of the contest, the date and time and contest and name of the referee.

From the above it will be seen that basket ball score card is provided, which is simple,

compact and one wherein a complete record of the individual players as well as the team as a whole may be kept.

The invention having been set forth what is claimed as new and useful is:—

A basket ball score card comprising right and left hand sections similarly marked, each of said sections being provided with indicia correspondingly positioned for the

different positions of players and in horizontal alinement, and indicia of the corresponding players score adjacent the name indicia, whereby scores of the first and second half of a game may be indicated.

In testimony whereof I hereunto affix my signature.

JOHN E. STEMPLE.
